MACHINE FOR RAISING METAL SPINES

Anthony F. Hoesel, Chicago, Ill., assignor to Thermek Corporation, Chicago, Ill., a corporation of Delaware

Application February 5, 1938, Serial No. 188,957

22 Claims.

(Cl. 29—1)

This invention relates to a method of and machine for raising spines from a solid surface, customarily of metal. In the application of Kritzer, Serial No. 172,176, filed November 1, 1937, there is disclosed a heat radiating member comprising a pipe from the surface of which there extends spines attenuating from the base to a sharp tip. As disclosed in that application, the spines are provided with a cross section which is noncircular in order to increase the ratio of heat transfer surface to mass. The spines disclosed therein are of a size too small and in number too numerous to permit, in a commercial sense, of individual joining to the pipe surface, such as by soldering or welding. This pipe surface has spines whose density is of the order of that obtaining in a coarse, wire hairbrush. Obviously, a heat radiating member of this type is of little commercial value unless a convenient, cheap and effective process and machine is devised for the quantity production thereof. It is, therefore, an object of this invention to devise a method of and a machine for making such a heat radiating member.

In the machine to be described, the spines are raised from the outer surface of a round member. However, it is obvious that the method may be easily applied to members having different shapes, and indeed, may be applied to flat metal plates. In general, the method contemplates the cutting of a sliver of metal for the major portion of its length along a line at a slight angle to the length of the metal, in the case of a pipe this being along an angle to the axis of the pipe. The base of the spine is then cut along an angle greater than the first angle and at the same time the entire spine is raised up from the metal surface. Preferably, a single cutter suitably shaped operates on one complete spine. In order to cover the surface with spines, a new portion of the metal surface is presented and a cutter thereupon repeats the cycle. In the case of a pipe, a substantially continuous feeding of the pipe in the direction of its length is present which tends to place the various spines along a helix having a uniform pitch. This, however, may be varied by means of intermittent feeding, well known in the machine art, so that a series of spines around the pipe on the circumference of a circle will be raised and thereafter the next succeeding series will be raised at a distance from the first. These differences, however, are considered to be within the scope of the general description and claims of both the method and the machine. To the extent that this machine duplicates certain fea-

tures present in certain types of milling machines, it is understood that as many changes within the machine are possible as are present within various kinds of milling machines analogous thereto.

The machine in general, comprises a plurality of cutters circularly arranged on a cutting head. This cutting head is adapted to revolve the cutters substantially tangent to the pipe with the cutting edges below the line of tangency so that a cutting action is obtained. One cutter is adapted to raise a sliver and thus perform a complete operation for making a spine. The entire cutting head at the same time is revolved around the pipe so that the succeeding cutter is presented to a fresh pipe surface. This planetary motion of the cutting head with respect to the pipe is at an angular speed substantially less than the angular speed of the cutters around the cutting head center. In fact, it is possible to merely have one cutter make a complete revolution and strike the pipe surface at a fresh spot each time to raise all the spines. However, it is preferred to have a plurality of cutters, adjacent cutters raising adjacent spines so that the same cutter will raise two spines separated by as many intervening spines as there are additional cutters on the cutting head. Obviously, the pipe may be turned instead of the cutting head.

Each cutter is provided with a cutting edge whose major length is at a small angle to the pipe axis, the angle being an angle of lag with respect to the direction of motion of the cutting edge against the pipe surface. The rear of the cutter is adapted to start the cutting operation first and cut the spine from the tip toward the base. The cutting edge slopes downwardly toward the pipe axis—in other words, extends deeper into the metal as the front of the cutter is approached. The last portion of the cutting edge is distorted to form a rearwardly curvilinear edge and swing the angle of shear of the metal from the former slight small angle to a large angle of the order of 90 degrees so that the front of the cutter slips behind the spine and raises the spine up and clears the same to pass the spine. In this way the component tending to shear the metal is reduced from practically 100 degrees to zero at which value the cutter merely slides by the spine. The very slight initial component tending to raise the spine is increased until the spine is raised up to clear the cutter.

Figure 4 is a section on 4—4 of Figure 1.

Figure 5 is a sectional detail on 5—5 of Figure 4.

5 Figure 6 is a sectional detail on 6—6 of Figure 4 showing the pipe gripping means.

Figure 7 is a detail of the cutting head.

Figures 8 to 11, inclusive, show the various stages in the cutting and raising of a spine.

10 Figure 12 is an end view of a pipe having spines formed thereon by the machine.

Figure 13 is a side view of the pipe shown in Figure 12.

15 Figure 14 is a detail showing the path of a spine from the pipe metal.

Figures 15 to 18, inclusive, are details of a cutter in various stages of manufacture.

Referring to the drawings, a base 10 of iron is supported on legs 12. This base has a plurality 20 of upstanding supports 13 to 17 inclusive, suitably bolted thereto and adapted to support the various pieces of mechanism composing the machine. Supports 13, 14 and 17 are provided with bearings 20, 21 and 22 respectively. Rotatively 25 mounted in these bearings is a main drive shaft 24 extending for substantially the length of the machine. Carried by the drive shaft near the front end of the machine—and hereafter this portion of the machine will be designated as the 30 front end—is a sprocket wheel 25 driven by a chain 26 and adapted to be driven from a suitable source of power.

The feeding mechanism (Fig. 3) of the machine will now be described. Carried by shaft 24 at the rear end thereof is a gear 28. This gear meshes with another gear 29 carried by a stub shaft 30 rotatively mounted in bearings 31 and 32 carried by supports 17 and 15 respectively. Stub shaft 30 carries a worm 33 which drives a worm gear 35 rigidly mounted on a feed drive shaft 36. 40 This feed drive shaft is journaled in suitable bearings in upright supports 38, 39 and 40 rigidly bolted to base 10 and to upright 16.

Feed drive shaft 36, in general, drives a plurality 45 of members spaced around the pipe and adapted to grip the pipe tightly and feed it forward toward the front cutting end of the machine. Referring to Figure 3, wherein the feed mechanism is detailed, feed drive shaft 36 carries a pair of bevel gears 42 and 43 facing in opposite directions with their teeth outwardly disposed and preferably mounted between supports 39 and 40. Between the spaced bevel gears 42 and 43 is a feeding wheel 45 having a plurality 50 of parallel grooves 46 cut therein. As clearly shown in Figure 3, the feeding wheel has a concave contour preferably of the same shape as that of pipe 50 to be fed thereby. Flanking supports 39 and 40 are supporting members 52 and 53 suitably carried by supports 38, 39, 40 and 16. Supporting member 53 carries an eccentric bearing 54 whose axis is perpendicular to that of feed drive shaft 36. Rotatively disposed in eccentric bearing 54 is a feed stub shaft 55 extending downwardly toward base 10 and suitably supported in a bearing in the base of the same general type as eccentric bearing 54.

Support 52 and base 10 similarly carry a feed stub shaft 56 parallel to the first stub shaft 55 and disposed on the other side of feed roller 45. Both feed stub shafts 55 and 56 carry bevel gears 60 to 63 inclusive, all identical with the companion bevel gears 42 and 43. The bevel gear pair 60 and 61 have a feed roller 64 disposed therebetween while the opposed pair of

gears 62 and 63 have a feed roll 65 therebetween. Both feed rolls 64 and 65 are identical with feed roll 45 so that further description is unnecessary. As clearly evident in Figure 3, the various feed rolls are disposed at 90 degrees to each other. An additional feed stub shaft 68 suitably journaled between supports 39 and 40 carries bevel gears 70 and 71 with a feed roll 72 therebetween. As is clearly evident from Figure 3, all the bevel gears are the same size and thus drive the four 10 feed rolls at the same speed. In practice, the feed rolls are so adjusted as to tightly grip pipe 50. It is preferable to provide eccentric bearings, such as 54, for all the feed driving shafts so that the gripping action on the pipe may be 15 adjusted to provide the desired feeding force and support against torsional movement of the pipe due to the action of the cutting mechanism. Such adjustment may be made in any desired manner and to any desired degree. 20

During a cutting operation on the pipe, the end of the pipe emerging from the front of the machine at the cutting head is subjected to a strain which tends to rotate the pipe and deflect the pipe at the same time. In order to firmly 25 support the length of the pipe between the feed mechanism and the cutting mechanism, I have provided means whereby, in spite of the usual manufacturing tolerances of the pipe, it is nevertheless gripped firmly at all times and only permitted to move forward freely. This is accomplished in the following manner.

Referring to Figures 1 and 4—10 inclusive, a pillow block 75 is suitably supported upon members 14 and 15 of the base. This block is provided with an axial cylindrical bore 76 within which is disposed hub 77 of a sun gear 78. Pillow block 75 is preferably slotted at 79 and provided with clamping bolts 80 which tend to contract the bore of the block so that a tight 40 grip upon the hub 77 is effected. Hub 77 of the sun gear itself is slotted at 81 to form a plurality of tongues so that the contraction of bore 76 is transmitted by hub 77 to a long stationary sleeve 83. As clearly evident in Figure 4, sleeve 45 83 has a cylindrical bore 84 within the region encompassed by the sun gear and its hub and thereafter the sleeve bore is reduced to form a cylindrical chamber 85. It should be noted that cylindrical chamber 85 does not extend to the end 50 of the sleeve 83 but instead has a shoulder 86 defining a slightly smaller bore 87 which finally terminates in an outwardly tapering conical chamber 88 at the forward end of the sleeve.

Disposed within sleeve 83 is a pull tube 90 55 having one end 91 disposed within sleeve 83 near the feeding mechanism. Enlarged portion 91 is adapted to snugly fit inside of chamber 84. Around pull tube 90 within chamber 84 is a coil spring 92 which is maintained in position between the shoulders formed by enlarged end 91 of the tube and reduced chamber 85. The front end of pull tube 90 is threaded at 94 on the interior thereof. A slotted collet 95, the main body of which is tapered to fit tapered bore 88, has its 60 reduced end 96 screwed into the threaded end 94 of tube 90. As is clearly evident from the drawings, coil spring 92 tends to expand against enlarged end 91 of the tube and pull slotted collet 95 into the tapered channel 88. The entire tube length 90 is preferably large enough to comfortably clear pipe 50. However, collet 95 is just large enough to engage pipe 50 within any desired tolerance due to variations in pipe 65 size. The angle of taper of the collet is prefer- 70 75

ably small enough so that any component of force perpendicular to the pipe, as side thrust of the cutting head, will have no effect upon the collet movement. Thus, I have found that for 5 tubing having an outside diameter of about .840 inch and an inside diameter of $\frac{1}{8}$ inch, that a collet angle of about 10 degrees is satisfactory even if rather heavy cuts are taken. This, however, is a matter of design and depends upon the 10 wall thickness of the pipe, upon the depth of the cut, and the hardness of the pipe, as well as the amount of permissible side play. By choosing a small collet angle, it is clear that the ratio of side thrust intensity to deflection of pipe is 15 greatly increased so that deflection may be reduced to a negligible value.

Thus it is evident that upon the turning of the main drive shaft 24 of the machine that the various feed wheels gripping the pipe from four sides 20 will feed the pipe forward. The spring biased collet is adjusted so that the pipe moves forward toward the front of the machine and is tightly gripped very near to the point of cutting in spite of possible variations of tube size. The spines 25 are cut on the pipe just as it emerges from the front of the machine at the collet 95. For this purpose a cutting head revoluble about the entire pipe is provided.

The cutting head comprises a casting 100 adapted to revolve around sleeve 83. Just beyond sun gear 78 a shoulder 101 is formed on sleeve 83 and the remainder of the sleeve toward the front of the machine is reduced in size to form a fixed shaft 102. Disposed at the 35 ends of shaft portion 102 are channel ball-bearing races 103 and 104 having a series of ball-bearings 105 and 106 respectively and retained in place by the outer race members 107 and 108. Outer race members 107 and 108 of the ball-bearings are driven into the ends of casting 100 so that this casting is rotatable about shaft portion 102. Casting 100 carries, or has formed thereon around the outside, a gear 110 which meshes with a gear 111 mounted upon main drive shaft 24. Thus, as the drive shaft turns, the 45 entire casting 100 is rotated upon shaft portion 102.

Casting 100 has rotatably mounted therein in an eccentric position a cutter shaft 112 which extends in spaced parallel relationship to the axis of the pipe 50 upon which the machine operates. This cutter shaft 112 is supported at spaced points by means of roller bearings 113 and 114 in rotatable relation to casting 100. In order to provide 50 dynamic balance to the entire casting head, I prefer to form casting 100 in such a manner that a heavy flange 115 is formed diametrically opposite the mounting for the cutter shaft 112. By suitably proportioning the metal, the moments 55 of inertia of different parts of the entire cutting head with reference to the center of shaft 102 may be equalized and thus reduce vibration.

The rear end of cutter shaft 112 carries a gear 118 maintained in place by a nut 119. Gear 118 is adapted to mesh with sun gear 78 and be turned thereby as gear 118 revolves around stationary sun gear 78. The front end of the cutter shaft 112 carries a cutter support body 120 rigidly locked in position by means of a nut 121. It is 65 clear, therefore, that with reference to Figure 1, if main drive shaft 24 is turned clockwise as seen from the front of the machine, the entire cutting head will be turned anti-clockwise around pipe 50 as a center, while the cutter body 120 will be 70 rotated anti-clockwise by virtue of the rotation 75

of gear 118 around stationary gear 78. The gear ratios are so chosen that cutter shaft 112 is turned at a decidedly greater speed than the entire cutting head around stationary shaft 102.

Referring now to Figures 7 and 15-18 inclusive, 5 the cutter head 120 carries a plurality of cutter elements 125. Each cutter 125 has a rear serrated surface 126 which is driven into correspondingly shaped slots in head 120 so that each cutter is rigidly held by the head. The cutter top 10 face 127 has an active cutting edge composed of a substantially straight portion 128 terminating in a rearwardly (with reference to the motion of the cutting edge) curved edge 129. The leading 15 face 130 of the cutter extends to an edge 131 intersecting the front side 132. However, near the top of the cutter, edge 131 is relieved by rounding off the metal so that front face 130 gradually merges into front side 132. The rear side of the 20 cutter (with reference to facing the machine from the front) 133 opposite front side 132 is squared off to fit true against the cutter head. The top face 127 of the cutter is ground down to permit cutting edges 128 and 129 to function.

In practice, a blank 125 is prepared with 25 serrated rear face 126 but otherwise of a generally rectangular shape. The blanks are driven into cutter head 120. The outer faces 136 of the blanks 125 are then circle ground carefully to provide top face 137 by revolving the cutter head 30 so that all cutters are the same. It will be noted that front side 132 of the cutter is longer than rear side 133 with the curved edge 129 extending outwardly from the cutter head more than the free end of the straight cutting edge. Obviously, 35 since curved edge 129 digs into the metal deeper, this diametral taper is necessary. Thereafter the edge 131 is ground away at the top portion of the cutter to cause surface 130 to gradually and continuously merge into surface 132. This may 40 be done by removing the cutters from the head and grinding to a predetermined curve. The bottom of the cutter is left flat to permit hammering the cutter home into the head. Then top face 137 is carefully ground down below cutting edges 45 128 and 129 just enough to permit the top face 127 of the cutter to clear the pipe surface and permit proper cutting action.

Now referring to Figures 8-11 inclusive, the 50 straight cutting edge 128 of the cutter shears a sliver 140. Inasmuch as cutting edge 128 tapers toward the pipe surface, the sliver 140 will taper from a sharp tip to its base. In practice, edge 128 also has a slight angularity with respect to the pipe axis or its own axis of rotation. The 55 free tip of edge 128 strikes the metal first. An angle of about 20 degrees to the pipe axis of cutting edge 128 has been found to be satisfactory though other angles may be used. Ordinarily bed 141 of the spine would be disposed at 60 this angle of 20 degrees to the pipe axis. However, due to the rotation of the cutter head about the pipe as well as the forward feed of the pipe all operating continuously, the direction is somewhat changed and, as shown in Figure 14 is parallel for a particular gear set-up. Obviously, this 65 may be varied. As the straight cutter edge bites into the pipe surface, the sliver or spine 140 is pushed out of the way of the advancing cutter. As the curved edge 129 strikes the metal, the 70 angle of shear is rapidly changed from its original small value to a full 90 degrees. As the angle of shear increases, the component tending to raise up the spine increases so that in Figures 10 and 11, the curved edge 129 of the cutter really 75

- slips around the bottom of the spine, straightens the spine to clear the cutter and leaves the spine standing. Due to the taper of the entire cutter edge to produce the spine taper, the wall of the pipe is tapered down under the cutter. Thus, Figures 8-11 really show a pipe portion on whose entire 360 degrees of circumference spines have been cut but all of which spines have been removed except the last one being formed.
- 10 The initial 20 degree angle is preferably obtained by having the straight cutting edge 128 perpendicular to the cutter sides and disposing the cutters at the 20 degree angle in the head as shown in Figure 2.
- 15 It is clear that since one cutter produces one spine, the number of spines raised around one pipe journey of the head will be the number of cutters multiplied by the ratio of gear teeth, of 18 and 118. The pitch will be determined by the 20 gear ratios of the pipe feeding means and may be computed in a manner similar to any screw cutting or milling machine. The depth of cut of each cutter is a matter of choice, as is the 25 length of the cutter to determine the spine length and angle of cut. By changing gears various arrangements of spines are possible.
- What is claimed is:
1. In a machine for forming and raising spines on a surface, the combination of means for holding said metal surface, a cutter having a substantially straight cutting edge with one end of said cutting edge curved rearwardly of said straight portion, and means for continuously rotating said cutter relatively to said surface to 35 consecutively cut slivers from the surface.
  2. In a machine of the character described, the combination of a cutter having a straight cutting edge terminating in a rearwardly curved cutting edge portion, means for holding a piece of metal, and means for continuously moving the cutter relatively to said metal so that said cutter digs into the metal and then comes out to form and raise a spine thereon.
  3. In a machine of the character described, 45 the combination of a cutter having a straight cutting edge portion terminating in a rearwardly curved cutting edge portion, means for holding a piece of metal to be operated upon, means for obtaining a cutting motion between said cutter and metal so that said cutter digs into the metal and then comes out to form and raise a spine, and feeding means for presenting a fresh portion 50 of the metal to the cutter for repeated cutting operation.
  4. In a machine for making and raising spines on a cylindrical surface, the combination of a cutter having a substantially straight cutting edge portion terminating in a rearwardly curved cutting portion, means for imparting cutting 55 movements to said cutter at substantially right angles to the straight portion of the cutting edge with the cutting edge tilted with respect to the cylindrical surface so that the curved rear portion of the cutter extends deepest into the metal.
  5. In a machine for operating upon a cylindrical member, the combination of a plurality of feeding wheels angularly disposed around said cylindrical member adapted to tightly grip said member and impart longitudinal motion thereto 60 in one direction only, a gang of rotary cutters operating on a portion of the pipe and adapted to successively cut longitudinal strips from the pipe and to impose transverse forces thereon, means on the cutters for bending cut strips out of the path 65 of the rotary cutter, and expandible means dis-

posed adjacent to said last named operating means adapted to yield during feeding motions of said member but to tightly grip said member and resist movement thereof in transverse direction.

6. In a machine for operating upon a pipe, the combination of feeding means adapted to tightly grip said bar and feed said bar longitudinally in one direction only, a gang of cutters adapted to successively operate on said pipe and to create 10 transverse forces on said pipe, the cutters being provided with means for bending the strips cut from the pipe transversely out of the path of the cutter, and means adjacent said cutting means for freely feeding said pipe but tightly gripping 15 said pipe against transverse movement, said means comprising an expansible element surrounding said pipe and resiliently urged against the direction of feed and adapted to contract when moving against the direction of feed. 20

7. In a machine of the character described, the combination of means for feeding a pipe longitudinally thereof, a cutting head carrying at least one cutter provided with a leading face and edge adapted to cut a spine from the surface 25 of said metal rod and bend the spine transversely to the axis of the pipe, means for rotating said cutting head in a plane substantially perpendicular to the pipe axis, said cutter being mounted in said head so its leading face and 30 edge are at a slight angle to the rod axis.

8. In a machine of the character described, the combination of means for feeding a metal pipe longitudinally thereof in one direction, a cutting head carrying a cutter, means for revolving said 35 cutting head in a plane substantially perpendicular to the rod axis with said cutter adapted to shear a metal spine from the surface of the pipe, said cutter having a cutting edge inclined with respect to the axis of rotation, and means for 40 bending the spine from the surface of the pipe while leaving one end of the sheared strip attached to the pipe.

9. In a machine of the character described, a 45 base, a plurality of feed wheels mounted on said base and adapted to engage a rod surface to feed said rod longitudinally, a cutting head carried by said base at a distance from said feed wheels, a plurality of cutters mounted in said cutting head, means for revolving said head to cause said 50 cutters to operate upon said rod, each cutter having a substantially straight cutting edge inclined with respect to the axis of rotation of the head with the end of the straight edge farthest from the axis of rotation terminating in a rearwardly directed curved cutting edge, and means for imparting relative rotary movement between said cutting head and said rod in a plane perpendicular to the rod axis and at a speed substantially lower than the speed of rotation of 60 said cutting head on its own axis whereby each cutter raises a spine on the surface of the rod. 55

10. The structure of claim 9 wherein each cutter has its cutting edge askew to provide a leading end of the cutter at the end of the cutting 65 head remote from the curved portion of the cutter.

11. In a machine for raising spines from a wall, the combination of a cutter movable bodily in a circular path, and provided with a cutting edge 70 inclined to cause it to intersect and pass out of the same face of the wall along different lines and initially gouge out a point of the stock and then continue the cut transversely of the circular path of the cutter to cut out a spine of the 75

desired length and with means for terminating the cut to leave the last end of the spine integral with the stock and bending the remainder out of the circular path of the cutter, means for continuously driving the cutter in a circular path for successive cuts, and mechanism for imparting relative movement to the gouging means and the wall for progressively cutting strips from the wall, and so the gouging means will clear the attached ends of previously cut strips.

12. In a machine for raising spines from a pipe, the combination of a cutter provided with a cutting edge inclined to cause the edge to intersect and pass out of the same face of the wall along different lines and initially gouge out a point of the stock and then continue the cut transversely of the path of the cutter to cut out a spine of the desired length and with means for terminating the cut to leave the last end of the spine integral with the stock and bending the remainder out of the path of the cutter, means for continuously driving the cutter so its leading edge will move in a path transversely to and for successive cuts, and mechanism for imparting relative movement to the cutter and wall to progressively cut strips from one face of the wall, and so as to clear the attached ends of previously cut strips.

13. In a machine for raising spines from a pipe, the combination of a cutter provided with a cutting edge inclined to cause the edge to intersect and pass out of the same face of the wall along different lines and initially gouge out a point of the stock and then progressively continue to cut transversely of the path of the cutter to cut out a spine of the desired length and with means for terminating the cut to leave the last end of the spine integral with the stock and bending the remainder out of the circular path of the cutter, power-driven means for continuously moving the cutter in a circular path for successive cuts, and mechanism for imparting relative rotary movement to the cutter and wall for progressively cutting strips in circumferential succession from the stock in one face of the wall.

14. In a machine for raising spines from a pipe, the combination of a series of bodily rotatable cutters, each provided with means for gouging a strip from the pipe-wall, leaving one end of the strip integrally attached to the wall, means for continuously moving the cutters in a circular path for successive cuts into the wall, and mechanism for imparting relative movement to the cutters and the wall so the cutters will progressively gouge strips from the stock in one face of the wall in helical succession.

15. In a machine for raising spines from a pipe, the combination of a series of cutters movable in a circular path, each provided with a cutting edge and leading face inclined to path of movement of the cutters to intersect and pass out of the periphery of the pipe for gouging a strip from the wall, leaving one end of the strip integrally attached to the wall, means for continuously rotating the cutters for successive cuts into the wall, and means for imparting relative movement to the cutters and the wall so the cutters will progressively cut strips from the stock in one face of the wall, in circumferential succession.

16. In a machine for raising spines from a pipe, the combination of a rotary cutter provided with a cutting edge and leading face inclined to cause the edge to intersect and pass out of the periphery of the wall along different lines and

gouge a point of the stock and progressively continue the cut transversely of the path of movement of the cutter to cut out a spine of the desired length and with means for terminating the cut to leave the last end of the spine integral with the stock and to bend the remainder out of the circular path of the cutter, means for imparting rotary movement to the cutter for successively cutting a strip from the wall, and means for imparting relative movement to the cutter and pipe for producing cuts in succession in the pipe.

17. In a machine for raising spines from a pipe, the combination of a rotary cutter provided with a cutting edge and leading face inclined to cause the edge to intersect and pass out of the periphery of the wall along different lines and gouge a point of the stock and progressively continue the cut transversely of the path of movement of the cutter to cut out a spine of the desired length and with means for terminating the cut to leave the last end of the spine integral with the stock and to bend the remainder out of the circular path of the cutter, means for imparting rotary movement to the cutter for successively cutting a strip from the wall, means for imparting relative movement to the cutter and pipe for producing cuts in circumferential succession in the pipe, and means for imparting relative movement to the cutter and wall lengthwise of the pipe to produce cuts in longitudinal progression.

18. In a machine for raising spines from a pipe, the combination of a rotary cutter head provided with a series of cutters, each provided with a cutting edge and leading face inclined to cause the edge to intersect and pass out of the periphery of the wall along different lines and initially gouge out a point of the stock and continue the cut transversely of the path of movement of the cutter to cut out a spine of the desired length and with means for terminating the cut to leave the last end of the spine integral with the stock and bending the remainder out of the circular path of the cutter, mechanism for imparting rotary movement to the cutter head for successively cutting a strip from the wall, mechanism for imparting relative movement to the cutter and pipe for producing cuts in circumferential succession in the pipe, and mechanism for imparting relative movement to the cutter and wall lengthwise of the pipe, to produce cuts in longitudinal progression.

19. In a machine for raising spines from an element having a cylindrical wall, the combination of a series of rotary cutters, each having a cutting edge and leading face inclined to cause the edge to intersect and pass out of the periphery of the wall along different lines and initially gouge out a point of the stock and continue the cut transversely of the path of movement of the cutter to cut out a spine of the desired length and with means for terminating the cut to leave the last end of the spine integral with the stock and bending the remainder out of the circular path of the cutter, and means for imparting planetary movement to the cutters, for producing cuts in circumferential succession around the periphery of the wall.

20. In a machine for raising spines from a wall, the combination of a cutter for cutting a strip from the stock in a face of the wall the cutter being provided with a cutting edge and a leading face inclined to cause the edge to intersect and pass out of the same face of the wall along different lines and gouge out a point of the stock

- and progressively continue the cut transversely of the path of the cutter to cut out a spine of the desired length and with means for terminating the cut to leave the last end of the spine integral with the stock and bending the remainder out of the path of the cutter, means for operating the cutter to consecutively cut strips from the wall with one end integrally attached, and mechanism for relatively moving the cutter and the wall to produce longitudinally and partially overlapping cutting strokes into the wall, which clear the attached ends of previously cut strips.
21. A machine for forming spines of a metal surface comprising means for holding the metal surface upon which the said spines are to be formed, means for cutting a sliver of metal with one end of said sliver only free from said surface provided with a leading face and cutting edge inclined for changing the cutting angle to reduce the cutting component and create a component for raising the sliver and for bending the sliver out of the path of the cutter and leaving

one end attached to the surface, and means for continuously operating the cutting means to consecutively cut the slivers from the surface, and means for operating the cutter to intersect and pass out of the same face of the wall and bending 5 the spines away from the wall.

22. A machine for raising spines on a wall of stock for heat exchange elements comprising a cutter, means for continuously moving the cutter bodily in a circular path, the cutter being 10 provided with a cutting edge inclined to cause the edge to intersect and pass out of the same face of the wall along different lines and initially gouge out a point of the stock and then progressively continue the cut transversely of the cutting plane to cut out a spine of the desired length, and with means for terminating the cut to leave the last end of the spine integral with the stock and bending the remainder out of the plane of the cutter.

ANTHONY F. HOESEL.
